UNITED STATES PATENT OFFICE.

KARL BAUMANN, OF URMSTON, ENGLAND, ASSIGNOR TO WESTINGHOUSE ELECTRIC & MANUFACTURING COMPANY, A CORPORATION OF PENNSYLVANIA.

ELASTIC-FLUID TURBINE.

Application filed September 8, 1924, Serial No. 736,639, and in Great Britain September 12, 1923. Renewed August 9, 1928.

This invention relates to that type of elastic fluid turbine wherein diaphragms carrying stationary blades or nozzles are housed in a stator of substantially regular shape formed 5 separately from the turbine casing and arranged within the latter so that motive fluid can gain access to the exterior as well as to the interior thereof, the arrangement being such that motive fluid can surround the internal stator and maintain it at substantially 10 the same temperature as the diaphragms so that any expansion or contraction of the latter due to temperature variations will be compensated by equivalent expansion or contraction 15 of the internal stator.

According to the invention the diaphragm carrying stator is supported at one end, preferably the high pressure or inlet end, by a diaphragm or spider which is secured at or 20 near its inner periphery to some part of the turbine which is substantially unaffected by irregular expansion or contraction of the turbine casing, as for instance the gland or bearing housing, and is housed at its outer 25 periphery in a groove or grooves in the external cylinder or in some part or parts connected therewith, sufficient radial clearance being provided to permit of differences of expansion and contraction between the diaphragm or spider and the turbine casing. The other end of the diaphragm carrying stator may be supported by a spider which 30 also may be connected with some part of the turbine which is substantially unaffected by irregular expansion or contraction of the turbine casing, as for instance the gland or bearing housing at that end of the turbine. 35 Orifices are provided near the inlet end of the diaphragm carrying stator so that motive fluid is admitted to the exterior of the stator and a tight joint is made between the external cylinder and a suitable part of the stator 40 either by means of a flange on one or other of said parts which is received in a corresponding groove in the other part, provision being made for radial expansion of the stator, or piston rings engaging with suitable flanges 45 may be located between the casing and diaphragm carrying stator for this purpose.

50 The connection between the end of the stator and the aforesaid diaphragm or spider may be made in a variety of ways. For ex-

ample, the diaphragm or spider may be formed with an annular groove on the face thereof, the end of the stator being received 55 in said annular groove and secured by suitable bolts or a flange may be provided on the face of the diaphragm or spider forming a rebate to receive the end of the stator, said flange may have an undercut groove or recess 60 to receive a corresponding flange on the outer cylindrical periphery of the diaphragm carrying stator.

The steam inlet chamber between the end 65 of the stator and the end of the turbine casing may be subdivided into compartments for nozzle cut-out governing, each compartment being separated by ribs projecting inwardly from the end of the turbine casing. When the stator is supported by a diaphragm a 70 tight joint between the diaphragm and the edges of the ribs is secured by means of bolts passing through said diaphragm into the inside of the turbine end casing parallel with the turbine axis. These bolts are sufficiently 75 long and flexible to permit expansion of the diaphragm in a radial direction.

Rotational movement of the internal stator may be prevented in a number of ways. For 80 example lugs may be cast on the turbine casing which are adapted to engage or be connected with the longitudinal flanges uniting the several parts of which the stator is formed.

By way of example reference will now be 85 made to the accompanying drawings wherein Figs. 1 to 4 are longitudinal sections through the top halves of steam turbines embodying different constructional forms of the invention and Fig. 5 is a section on the plane V—V 90 of Figs. 1 to 3. In each figure certain parts which should appear behind the plane of the section are omitted for clearness of illustration.

In each form illustrated the turbine 95 comprises a casing 1, rotor 2, and internal stator 3 in which are housed the diaphragms 4. The stator 3 is formed in two or more parts united by longitudinal flanges 5 which for convenience are indicated in broken lines at the top of the stator 3; their actual position is determined by practical considerations, a convenient position being at or near the horizontal joint between the top and bottom 100

halves of the casing 1 where they may be secured between lugs which prevent rotation of the stator 3 relative to the casing 1.

- In each of the forms illustrated by Figs. 5 to 3 the first diaphragm or nozzle plate 4^a at the high pressure end of the turbine is secured at or near its inner periphery to the gland or bearing housing 6 by studs or set screws 7 and is received at its outer periphery 10 in a groove 8 turned in the interior of the casing 1, sufficient radial clearance being provided to compensate differences of radial expansion and contraction of these parts. The steam inlet chamber 9 between the diaphragm 15 or nozzle plate 4^a and the end of the casing 1 is subdivided, as illustrated in Fig. 5, into compartments 10, 11, 12 and 13 for nozzle cut out governing by ribs 14, 15, 16 and 17 projecting inwardly from the end of the turbine 20 casing. A steam tight joint between the edges of these ribs and the diaphragm 4^a is secured by means of bolts 18 which pass through said diaphragm into the end of the turbine casing and are sufficiently long to permit of radial expansion and contraction of the diaphragm 4^a. The stator 3 is connected, at its high pressure end, with the diaphragm or nozzle plate 4^a as hereinafter described and, at its low pressure end, with a spider 19 25 which is recessed into the gland or bearing housing 6 at that end of the turbine, sufficient clearance being provided at 20 to compensate differences of axial expansion and contraction between the casing 1 and stator 3. Holes 21 30 are formed in the stator 3 for the admission of steam to the exterior of the latter, at least one of these holes being preferably formed at the lowermost part of the stator to act as a drain.
- 40 In each of the constructions illustrated by Figs. 1 and 2 the stator 3 is connected at its high pressure end with the diaphragm 4^a by interfitting annular rims 22 and 23 formed on these parts, sufficient clearance being provided at 24 to permit of differences of axial expansion and contraction, and an annular flange 25 formed at or about the center of the stator 3 engages a groove 26 turned in the casing 1. This flange serves both to transmit to the casing 1 any end thrust set up in the stator 3 and to prevent leakage of steam between these parts, sufficient clearance being provided between the same and the base of the groove 26 to permit of differences of expansion and contraction between the stator 3 and casing 1.
- 45 The construction illustrated by Fig. 3 differs from that illustrated by Fig. 1 or Fig. 2 in that an annular spigot 27 on the rim 22 50 engages an annular groove 28 in the rim 23 and the co-operating flange and groove 25 and 26 respectively are replaced by a piston ring 29 housed within a groove 30 in the stator 3 engaging a smooth cylindrical face 31 55 turned in the casing 1, a series of holes 32 be-

ing provided in one wall of the groove 30 to admit steam to the inside of the ring 29. In this construction any end thrust set up in the stator 3 is transmitted to the casing 1 through the diaphragm 4^a, the stator being free to expand or contract throughout the whole of its length.

In the construction illustrated by Fig. 4 the stream inlet chamber 9 is not subdivided for nozzle cut out governing and the parts incidental to this arrangement are omitted. The stator 3 is fitted with sufficient axial clearances at 33 and 34 to permit of differences of axial expansion and contraction between the stator 3 and casing 1 into the first 80 diaphragm 4^a and a spider 19'. These latter parts are provided with spigotted hub portions 35 and 36 respectively which fit within correspondingly shaped portions of the gland or bearing housings 6 at opposite ends of the 85 turbine and the outer peripheries thereof are received with sufficient radial clearances to permit of differences of radial expansion and contraction between the stator 3 and casing 1, in grooves 37 and 38 formed in webs 39 and 40 90 respectively cast integral with the casing 1. An inwardly projecting flange or web 41 on the casing 1 engages an annular groove or recess 42 turned in the stator 3 and serves both to prevent leakage of steam between the stator 3 and casing 1 and to transmit to the latter any end thrust set up in the former, sufficient radial clearance being provided to compensate differences of radial expansion and contraction between these parts. As with 100 this arrangement steam can again free access from the inlet chamber 9 to the exterior of the stator 3, it is unnecessary to provide holes in the latter for this purpose.

While I have shown my invention in several forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:—

1. In a turbine, the combination of a casing, a diaphragm carrying stator disposed within the casing and means supporting at least one end of the diaphragm carrying stator from a part of the casing substantially unaffected by irregular expansion and contraction of said casing.
2. In a turbine, the combination of a casing, a diaphragm carrying stator disposed within the casing, a member for supporting at least one end of the stator from a part of the casing substantially unaffected by irregular expansion and contraction of said casing, and means fixedly securing said supporting member to said part.
3. In a turbine, the combination of a cas-

ing having a gland housing, a diaphragm carrying stator disposed within the casing, a member for supporting at least one end of the stator from the gland housing of the turbine casing and means fixedly securing said supporting member to said housing.

4. In a turbine, the combination of a casing, a rotor having a shaft and disposed within the casing, a diaphragm carrying stator surrounding the shaft, a circular member supporting the stator, means adjacent the shaft for fixedly securing the supporting member to the casing, a flange provided on the outer periphery of the supporting member, and a groove provided in the casing for receiving the flange.

5. In a turbine, the combination of a casing, a rotor having a shaft and disposed within the casing, a diaphragm carrying stator surrounding the shaft and the rotor, a circular member for supporting one end of the stator, means adjacent the shaft for fixedly securing the supporting member to the casing, other means remote from the shaft for flexibly securing the supporting member to said casing, and a complementary flange and groove connection between the outer periphery of the supporting member and the casing, said connection permitting relative radial movement therebetween upon unequal expansion or contraction of the supporting member and the casing.

6. In a turbine, the combination of a casing, a diaphragm carrying stator disposed within the casing, a rotor having a shaft and surrounded by the stator, a circular member at the high pressure end of the casing for supporting said end of the stator and forming with the casing a fluid admission chamber, means adjacent the turbine shaft for joining said supporting member to said casing, flexible means remote from the shaft connecting said supporting member to said casing, a complementary groove and flange connection between the outer periphery of the supporting member and the casing so arranged as to permit relative radial movement therebetween, means near the high pressure end of the stator permitting motive fluid to pass between said stator and said casing, and means remote from the high pressure end forming a fluid-tight connection between said stator and said casing.

7. In a turbine, the combination of a casing, a diaphragm carrying stator disposed within the casing, a rotor having a shaft and surrounded by the stator, a circular member at the high pressure end of the casing for supporting the stator and forming with the casing a fluid admission chamber, means adjacent the turbine shaft for fixedly joining said supporting member to said casing, flexible means remote from the shaft connecting said supporting member to said casing, a complementary groove and flange connection

between the outer periphery of the supporting member and the casing so arranged as to permit relative radial movement therebetween, means near the high pressure end of the stator permitting motive fluid to pass between said stator and said casing and a fluid-tight complementary flange and groove connection arranged between the stator and the casing remote from the high pressure end of the turbine, said connection permitting relative radial movement between said stator and said casing.

8. In a turbine, the combination of a casing, a diaphragm carrying stator disposed within the casing, a rotor having a shaft and disposed within the stator, a member arranged at each end of the stator for supporting said stator, means adjacent the shaft at the high pressure end of the turbine for fixedly securing said supporting member to the casing, and a sliding connection between the casing and the supporting member at the low pressure end of the turbine.

9. In a turbine having a casing, a rotor with a shaft and a diaphragm carrying stator surrounding the rotor, the combination of a transverse member arranged at each end of the stator and surrounding the shaft for supporting the stator, means fixedly securing the supporting member at the high pressure end of the turbine to the casing near the shaft, a sliding connection between the casing and the supporting member at the low pressure end of the turbine, and a complementary flange and groove connection between the stator and the casing permitting radial movement therebetween and preventing the flow of motive fluid over said stator to the low pressure end of the turbine.

10. In a multi-stage turbine, the combination of a casing, a rotor having a plurality of discs mounted thereon, a plurality of diaphragms interleaving with the discs, a stator disposed within the casing for supporting the diaphragm, a transverse wall forming with the casing a motive fluid chamber at the high pressure end of the turbine and supporting the high pressure end of the stator, means adjacent the rotor shaft for fixedly joining said transverse wall to the casing, means remote from the shaft for flexibly connecting said wall to said casing, a complementary flange and groove connection permitting relative radial movement between the wall and the casing around the outer periphery of the wall, a transverse member for supporting the stator at the low pressure end of the casing, and a sliding connection between said supporting member and the casing adjacent the rotor shaft.

11. In a multi-stage turbine having a casing and a diaphragm carrying stator disposed within the casing, the combination of a flange provided on the stator intermediate the ends thereof, a groove provided in

- the casing for receiving the flange and fixing the stator against longitudinal displacement in the casing, said groove permitting a radial expansion of the stator, and a transverse supporting member co-acting with the casing at each end of the stator for supporting said stator, said supporting member permitting freedom of longitudinal movement of the stator upon expansion or contraction 10 thereof away from its intermediate fixed point.
12. In a multi-stage turbine, the combination of a rotor with a plurality of discs and having a shaft, a plurality of diaphragms interleaving with the discs and a stator in which the diaphragms are mounted, a casing surrounding the rotor and the stator, a transverse wall surrounding the shaft and secured to the casing at the high pressure end of the 15 turbine and forming with the casing a motive fluid chamber, supporting means permitting relative longitudinal movement arranged between the transverse wall and the stator, a transverse member at the low pressure end 20 of the turbine surrounding the shaft for supporting the low pressure end of the stator and fixedly secured to said stator, a longitudinal sliding connection between the transverse supporting member and the casing, and 25 means intermediate the ends of the stator co-acting between the casing and the stator for securing said stator against longitudinal displacement in the casing.
13. In a turbine, the combination of a 30 casing, a rotor having a shaft and disposed within the casing, a diaphragm carrying stator surrounding the rotor, a member for supporting the high pressure end of the stator and forming with the casing a motive fluid chamber, and a plurality of ribs extending inwardly from the casing and co-acting with the supporting member for dividing the fluid chamber into a plurality of nozzle chambers.
14. In a turbine, the combination of a 35 casing, a rotor having a shaft and disposed within the casing, a diaphragm carrying stator surrounding the rotor, a member for supporting the high pressure end of the stator and forming with the casing a motive fluid chamber, and a plurality of radially extending dividing ribs formed on the casing and extending inwardly toward the supporting member for dividing said motive fluid chamber into a plurality of nozzle chambers.
15. In a turbine, the combination of a 40 casing, a diaphragm carrying stator disposed within the casing, a rotor having a shaft and disposed within the stator, a member arranged at each end of the stator for supporting said stator, a sliding connection between the casing and the supporting member at the low pressure end of the turbine, means fixedly securing the supporting member at the 45 high pressure end to the turbine casing,

sliding connection between the stator and the supporting member at the high pressure end of the turbine, and means co-acting between the stator and the casing at an intermediate point of the stator for fixing said stator 70 against longitudinal displacement in the casing.

16. In a turbine, the combination of a casing, a diaphragm carrying stator disposed within the casing, a rotor having a shaft and disposed within the stator, a member arranged at each end of the stator for supporting said stator and means supporting the supporting members from the casing.

17. In a turbine, the combination of a casing, a rotor having a shaft and disposed within the casing, a blade carrying stator surrounding the shaft, a circular member supporting the stator, means adjacent the shaft for fixedly securing the supporting member to the casing, a flange provided on the outer periphery of the supporting member, and a groove provided in the casing for receiving the flange.

18. In a turbine, the combination of a casing, a rotor having a shaft and disposed within the casing, a blade carrying stator surrounding the rotor, a member for supporting the high pressure end of the stator and forming with the casing a motive fluid chamber, and a plurality of ribs extending inwardly from the casing and co-acting with the supporting member for dividing the fluid chamber into a plurality of nozzle chambers.

19. In a turbine, the combination of a casing, a blade carrying stator disposed within the casing, a rotor having a shaft and disposed within the stator, a member arranged at each end of the stator for supporting said stator and means supporting the supporting members from the casing adjacent the shaft.

20. In an elastic fluid turbine, the combination of an outer casing, a rotor having a shaft and disposed within the casing, a blade carrying stator disposed within the casing and surrounding the shaft, means provided near each end of the stator for maintaining the same co-axial with the casing, and means preventing relative axial movement between the stator and the casing in one plane normal to the axis of the turbine, the parts of said stator outside of said plane being free to move axially relative to the casing to permit of longitudinal expansion and contraction of the stator independently of the casing.

21. In an elastic fluid turbine, the combination of an outer casing, a rotor having a shaft and disposed within the casing, a blade carrying stator having a high pressure end and a low pressure end and disposed within the casing and surrounding the shaft, means maintaining the high pressure end of the stator co-axial with the casing but permitting relative radial movement therebetween to permit said end of the stator to expand and 130

contract independently of the casing, means maintaining the low pressure end of the stator co-axial with the casing, and means preventing relative axial movement between the stator and the casing in one plane normal to the axis of the turbine, the parts of said stator spaced from said plane being capable

of axial movement relative to the casing, whereby the stator may expand and contract axially independently of the casing.

10

In testimony whereof, I have hereunto subscribed my name this 8th day of August, 1924.

KARL BAUMANN.
